DOCTOR BLADE FOR CALENDER ROLL
Howard E. Kuehn, Orange, Conn., assignor to
Farrel Corporation, Ansonia, Conn.
Filed Jan. 8, 1965, Ser. No. 424,422
10 Claims. (Cl. 15—256.51)

This invention relates to calendering apparatus, and more particularly relates to doctor blades used in conjunction therewith.

In apparatus for calendering materials, such as paper, bits of the material being calendered cling to the rolls. For high quality calendering the surfaces of the roll should be kept clean and free of foreign material in order that the material may be calendered to uniform dimensions and characteristics throughout its length and width. This is accomplished by the provision of a doctor blade for each roll which contacts the roll surface along essentially its entire length and strips contaminants from the surface of the roll as the roll moves past the doctor blade.

The doctor blade and the support therefor extend across essentially the entire face of the roll, and means are provided at either end of the doctor blade support for urging the doctor blade into contact with the roll at a predetermined pressure. Therefore, the contact pressure producing means essentially acts only at the ends of the doctor blade. The length of the doctor blade will, of course, be determined by the length of the face of the roll upon which the doctor blade is to operate, which may be twelve feet or more.

It may be appreciated that when doctor blades this long are urged into contact with the roll at its ends it is extremely difficult, if not impossible, to establish uniform pressure between the doctor blade and the roll along the length of the doctor blade. There will be deflection of the doctor blade along its length, the maximum deflection being in the center of the roll which is the maximum distance from the force producing means which urge the doctor blade into contact with the roll. As will herein-after be discussed, this deflection is somewhat analogous to the deflection of a beam between two points of support. Such deflection results in uneven pressure between the doctor blade and the roll along the length of the doctor blade and in turn causes heavy loading of the doctor blade against the rolls at the ends thereof and light loading of the doctor blade toward the center thereof away from the ends of the doctor blade.

The ultimate result of such uneven pressure distribution along the length of the doctor blade is severe wear on the end portions of the roll face with respect to the more central portion thereof. This is probably one of the most prevalent reasons for periodically regrinding and recontouring rolls in paper mills.

In view of the foregoing problems experienced with presently known calender roll-doctor blade arrangements, the present invention is intended to provide a doctor blade structure through which a substantially constant pressure between the doctor blade and the roll may be obtained and maintained along the length of the doctor blade.

Accordingly, an object of this invention is to provide a new and improved doctor blade.

Another object of this invention is to provide a new and improved doctor blade structure which will not create undesired wear in concentrated areas of the roll upon which it operates.

Another object of this invention is to provide a new and improved doctor blade assembly including means for maintaining the unit pressure of the doctor blade on the roll upon which it operates substantially constant along the length of the doctor blade.

2

A further object of this invention is to provide a doctor blade assembly having a new and improved means for regulating the pressure between the doctor blade and the roll upon which it operates.

5 Briefly stated, the invention in one form thereof comprises a hollow sleeve-like member upon which the doctor blade is mounted. The doctor blade mounting member is supported concentrically about and on a rigid shaft which is rotatable to bring the doctor blade into contact with the roll upon which it operates. Fluid pressure operated means are provided between the doctor blade mounting member and the shaft to controllably deflect the doctor blade mounting member along the length thereof and compensate for deflection of the doctor blade and thereby maintain substantially constant the unit pressure of the doctor blade against the roll along the length of the doctor blade.

The features of the invention which are believed to be novel are set forth with particularity and definitely claimed 20 in the concluding portion of this specification. The invention, however, both as to its organization and operation, together with further objects and advantages thereof, may best be appreciated by reference to the following detailed description taken in conjunction with the drawings in 25 which:

FIG. 1 is a front elevation of a calender including a doctor blade assembly embodying the invention;

FIG. 2 is a sectional view seen in the plane of line 2—2 of FIG. 1;

30 FIG. 3 is a sectional view seen in the plane of line 3—3 of FIG. 1;

FIG. 4 is a sectional view seen in the plane of line 4—4 of FIG. 3;

35 FIG. 5 is a view of a doctor blade seen in the plane of line 5—5 of FIG. 3.

FIG. 6 is a sectional view seen along the plane of line 6—6 of FIG. 3 with deflection imparted to the doctor blade support; and

40 FIG. 7 is a schematic diagram of a representative hydraulic circuit which may be utilized in the practice of the invention.

A calender utilizing a doctor blade assembly embodying the invention is illustrated in FIG. 1 and comprises a bottom calender roll 10 having a roll face 11. The roll necks or journals are rotatably supported in roll journal supports 12 and 13 carried on a frame illustrated as having leg portions 14. In a calendering operation roll 10 cooperates with other rolls thereabove exemplified by roll 15. It will be understood, of course, that a doctor blade is usually associated with each roll of a calender. Carried on legs 14 or made integral therewith are doctor blade assembly supports 16. Each of supports 16 carries a guide member 17 thereon having a guide way 18 therein. Slidably mounted on member 17 in guide ways 18 are bearing mounts 19. Bearing mounts 19 are adjustably positionable in guide ways 18 by means of a locating bolt 20 as more clearly shown in FIG. 2. By means of the guide member 17 and locating bolts 20 the doctor blade assembly may be positioned a predetermined distance from the axis of roll 10.

45 A doctor blade 22 is mounted in a holder 23 which in turn is mounted on a doctor blade carrier 24. Carrier 24 is mounted on a hollow shell-like doctor blade support member 25 by means of a plurality of gussets or ribs 26. 50 Doctor blade support member 25 is mounted on and coaxially spaced about a shaft 27. Shaft 27 at each end thereof has secured thereto end caps 28 which receive therein bearing blocks 29 which rest on a bearing 30 affixed to shaft 27. Shaft 27 at the ends thereof also carries thereon bearings 31 received in bearing mounts 19. Pinned to shaft 27 at either end thereof is the collar 32 of a lever

33 arranged to be actuated by the shaft or piston rod 34 of a fluid-operated cylinder 35 which is carried on a bracket 36 extending from each of supports 16. Levers 33 provide a means for cylinders 35 to rotate shaft 27 and the doctor blade assembly thereon into engagement with roll face 11, as indicated by the arc 37, FIG. 3. Mounted on shaft 27 and secured thereto as by welding are strip-like members 38 and 39 which extend the length of shaft 27 between bearings 29. In the illustrated embodiment of the invention, the strip-like members 38 and 39 are disposed substantially 180 degrees apart and define a plane substantially parallel to the plane of the surface of doctor blade carrier 24.

By virtue of the mounting of member 25 on shaft 27 through bearings 29, member 25 is normally rotatable on shaft 27. However, such rotation in one direction is prevented through the provision of torque transmitting lugs 40 which engage and butt against member 39 as most clearly shown in FIGS. 3 and 4. Lugs 40 are carried by member 25, for example, as by means of a headed bolt 41 threadably received into each lug.

The function of the torque transmitting lugs is to make the member 25 follow the motion of the shaft when cylinders 35 are operated to urge the doctor blade into engagement with the roll. It will be noted that as shaft 27 turns in the direction of the arrow A, FIG. 3, member 39 will act upon lugs 40 and produce equal and simultaneous rotation of member 25. The lugs 40 are disposed at either end of member 25, although others may be spaced therebetween.

Member 25, shaft 27, and members 38 and 39 define a longitudinally extending cavity. This cavity receives therein an expansible bladder 43. A fluid passage 44 is defined in member 25 and has a nipple 45 inserted therein which provides communication to the interior of bladder 43. In operation, the cylinders 35 are actuated and the piston rods 34 thereof act on levers 33 connected to shaft 27 to rotate shaft 27 in the direction of arrow A. As shaft 27 rotates member 39 thereon engages the lugs 40 and rotates member 25 together with doctor blade structure thereon and doctor blade 22 comes into engagement with face 11 of roll 10. At this time, due to the long length of the doctor blade it will deflect somewhat as exemplified in FIG. 5 and the pressure between the edge of the doctor blade and the roll face 10 will not be uniform along the length of the doctor blade. In FIG. 5, the amount of deflection is exaggerated for purposes of illustration. This may be readily appreciated by noting that the doctor blade is moved into contact with the roll face by the exertion of equal forces which are essentially at the ends thereof, the forces being exerted by the cylinders 35 and associated mechanism. In FIG. 5 the forces exerted on the ends of the doctor blade by the cylinders 35 are denoted by the arrows B and C. It will, of course, be understood that in the described structure the forces B and C reside without the ends of the doctor blade. However, for purposes of discussion they may be considered to be located at the ends of the doctor blade. This deflection of the doctor blades results in uneven pressure along the length thereof and the roll will experience greater wear at the ends thereof.

To overcome this unequal distribution of pressure, bladder 43 is expanded under fluid pressure and reacts against shaft 27 and members 38 and 39 to deflect member 25, as shown in FIG. 6, in a direction substantially perpendicular to members 38 and 39 which is also generally perpendicular to the plane of doctor blade support member 24. The deflection of member 25 is exaggerated for purposes of illustration. This deflection of member 25 due to the expansion of bladder 43, results in deflection of member 24 carried on member 25 and doctor blade 22 carried thereon. This resultant deflection of doctor blade 22 is due to the unit pressure exerted on the interior of member 25 by the pressure within bladder 43. It will be noted that the member 25 is supported at its ends on shaft 27 through bearing block 29 and bearing 30 and

therefore the deflection at the ends will be zero, increasing to a maximum at the center. The resultant deflection of member 25 is that of a beam uniformly loaded between two points of support. As member 25 is deflected as shown in FIG. 6, the ribs 26 thereon move therewith and produce deflection or bending of doctor blade carrier 24 along its length. The maximum bending of carrier 24 occurs at its mid-point and the curve thereof will follow the curve of carrier 24, FIG. 6. This deflection or bending of carrier 24 and doctor blade 22 is in a direction opposite to the deflection of the doctor blade produced by the loading of the ends thereof by vectors B and C; FIG. 5 which represent the forces exerted on member 25 through shaft 27 by the cylinders 35.

The total force exerted by the fluid pressure on shaft 27 and member 25 is selected to be approximately the same in magnitude as the total force acting between the doctor blade and the roll produced by cylinders 35. Therefore, the pressure per unit length between the doctor blade and the roll along the length of the doctor blade is more likely to be constant and resultant bending of the doctor blade support tends to be prevented. It will, of course, be appreciated that slightly higher or lower fluid pressure in bladder 43 could be used as a secondary function in the event that the calender operator might intentionally desire slightly higher contact pressure of the blade in the center of the roll or at the ends of the roll under certain operating conditions.

A suitable means for applying fluid pressure to both the cylinders 35 and bladder 43 is schematically illustrated in FIG. 7. This comprises a sump 51, a pump 52, a pressure regulating valve 53, a two-position four-way valve 54, and a pressure changing cylinder 55. In operation the pump 52 draws the fluid from sump 51 and applies it to a pressure regulating valve which determines the pressure at which the fluid will be applied the remainder of the system. The fluid is then applied to two-position four-way valve 54 and hence to a coupling 56, and from coupling 56 to cylinders 35. When fluid is applied to cylinders 35 from coupling 56 the piston shafts 34 are extended to move the doctor structure into contact with the roll. At the same time the fluid under pressure is applied from coupling 56 to pressure changing cylinder 55 to change the pressure applied to the bladder in a predetermined ratio. The pressure applied to the cylinders and bladder is determined by the setting of pressure-regulating valve 53. When the pressure in the cylinders and bladder is to be reduced a new setting is made on pressure-regulating valve 53, the two-position four-way valve 54 is shifted to its second position and operation reverse to that described takes place, in a well-known manner.

The structure of the pressure chamber and doctor blade support means disclosed herein is a preferred embodiment of the invention. Other structures including or defining a pressure chamber for deflecting or bending the doctor blade carrier which do not depart from the spirit and scope of the invention may occur to those skilled in the art. Accordingly, it is intended in the appended claims to cover all embodiments of the invention as well as modifications to the disclosed embodiment of the invention which do not depart from the spirit and scope of the invention.

What is claimed is:

1. In a calender having a calender roll, a frame, means rotatably supporting said calender roll on said frame and a doctor blade adapted to contact the roll along the face thereof; a hollow tubular support member for said doctor blade extending along the length of the roll, means including a force reacting means defining an elongated pressure chamber within said member, and means for introducing fluid under pressure into said chamber to deflect said member and the doctor blade carried thereon along their length, said chamber being so positioned within said hollow support member that the pressure in said chamber deflects said support member in a direction

which urges the doctor blade into contact with the roll along the length thereof.

2. In a calender having a calender roll, a frame, means rotatably supporting said calender roll on said frame and a doctor blade adapted to contact the roll along the face thereof; a hollow tubular support member for said doctor blade extending along the length of the roll, means at the ends of said support member for moving the support member so that the doctor blade thereon contacts the roll, means including a force reacting means defining an elongated chamber within said member, and means for introducing fluid under pressure into said chamber to deflect said member and the doctor blade carried thereon along their length, said chamber being so positioned within said hollow support member that the pressure in said chamber deflects said support member in a direction to urge the doctor blade into contact with the roll along the length thereof.

3. In a calender having a calender roll, a frame, means rotatably supporting said calender roll on said frame and a doctor blade adapted to contact the roll along the face thereof; a hollow tubular support member for said doctor blade extending along the length of the roll, means including a force reacting means defining an elongated pressure chamber within said member, and means for introducing fluid under pressure into said chamber to deflect said member and the doctor blade carried thereon along their length, said chamber being so defined within said hollow support member that the pressure in said chamber deflects said support member in a direction substantially perpendicular to the plane of the doctor blade.

4. In a calender having a calender roll, a frame, means rotatably supporting said calender roll on said frame and a doctor blade adapted to contact the roll along the face thereof; a shaft, means supporting said shaft on said frame, a hollow support member for said doctor blade extending along the length of the roll and coaxially mounted on said shaft, means at the ends of said shaft for rotating said shaft to move the doctor blade on said support member into engagement with the roll, means carried by said shaft and cooperating with said support member defining an elongated chamber, and means for introducing fluid under pressure into said chamber to deflect said member and the doctor blade carried thereon along their length, said chamber being so positioned within said hollow support member that the pressure in said chamber deflects said support member in a direction to urge the doctor blade into contact with the roll along the length thereof.

5. The apparatus of claim 4 further including an expandable bladder in said chamber to confine the fluid introduced therein.

6. In a calender having a calender roll, a frame, means rotatably supporting said calender roll on said frame and a doctor blade adapted to contact the roll along the face thereof; a support for the doctor blade comprising, a shaft, means rotatably supporting said shaft on said frame, means acting at the ends of said shaft for rotating said shaft, a sleeve-like member disposed about said shaft, and spaced therefrom to define a cavity therebetween, said member carrying said doctor blade thereon, an elongated expandable bladder in said cavity adapted to confine fluid under pressure, and means for introducing fluid under pressure into said bladder to expand said bladder so that said sleeve-like member is displaced from its

normal position with respect to said shaft, and said doctor blade on said member is urged toward the calender roll to tend to substantially equalize the pressure between the blade and the roll along the length of the blade.

5 7. In a calender having a calender roll, a frame, means rotatably supporting said calender roll on said frame and a doctor blade adapted to contact the roll along the face thereof; a support for the doctor blade comprising, a shaft, means rotatably supporting said shaft on said frame, means acting at the ends of said shaft for rotating said shaft, a sleeve-like member normally coaxially disposed about said shaft and supported thereon at its ends, said member carrying the doctor blade thereon, means carried on said shaft defining with said shaft and said 10 member an elongated cavity, means for introducing fluid under pressure into said cavity to deflect said member from its normal position with respect to said shaft so that a doctor blade on said member is urged toward the calender roll to tend to substantially equalize the pressure between the blade and the roll along the length of the blade.

20 8. The arrangement of claim 7 further including an expandable bladder in said cavity adapted to confine fluid under pressure.

25 9. The arrangement of claim 8 wherein said means carried on said shaft comprise strips of material substantially extending along the length of said shaft, said strips defining said cavity in such position relative to the position of the doctor blade on said member that upon application of fluid pressure to said bladder said member is deflected in a direction substantially perpendicular to the plane of the doctor blade.

35 10. In a calender having a calender roll, a frame, means rotatably supporting said calender roll on said frame and a doctor blade adapted to contact the roll along the face thereof; a support for the doctor blade comprising, a shaft, means rotatably supporting said shaft on said frame, a sleeve-like member coaxially disposed about said shaft and supported at its ends on said shaft, said member carrying the doctor blade thereon in a plane substantially tangential to said member, means carried on said shaft defining a cavity along the length of said member on the side of said shaft opposite the plane of the doctor blade, an expandable bladder in said cavity adapted to confine fluid under pressure, means for rotating said shaft to bring the doctor blade into contact with the roll, means for introducing fluid under pressure into said bladder to expand said bladder so that said member is displaced from its normal position with respect to said shaft and said doctor blade on said member is urged toward the calender roll to tend to substantially equalize the pressure between the blade and the roll along the length of the blade.
